UNITED STATES PATENT OFFICE.

RICHARD ROOST, OF MILWAUKEE, WISCONSIN, ASSIGNOR TO HUEBSCH MANUFACTURING COMPANY, OF MILWAUKEE, WISCONSIN, A CORPORATION OF WISCONSIN.

CLAMP FOR STOCKING-IRONERS.

1,243,346.

Specification of Letters Patent. Patented Oct. 16, 1917.

Application filed January 30, 1915. Serial No. 5,199.

To all whom it may concern:

Be it known that I, RICHARD ROOST, a citizen of the United States, and a resident of the city of Milwaukee, in the county of Milwaukee and State of Wisconsin, have invented certain new and useful Improvements in Clamps for Stocking-Ironers; and I do hereby declare that the following is a full, clear, and exact description of the same, reference being had to the accompanying drawings, and to the numerals of reference marked thereon, which form a part of this specification.

This invention relates to a clamp adapted to hold a sock or stocking stretched upon an ironing or drying device such as disclosed in the co-pending application for patent of Joseph Huebsch for "heated hosiery forms", filed June 8th, 1914, Serial No. 843,659. In the aforesaid invention the sock is drawn upon a suitable heated form, and is thus stretched to proper shape and then dried. It is necessary during such an operation to hold the sock at its open end by suitable clamping means of some sort to prevent the same creeping and shrinking as it is dried. Accordingly I have constructed a clamp which forms the subject matter of the present invention which is exceedingly efficient and peculiarly adapted for the purpose for which designed.

It is an object therefore of this invention to construct a clamp, the parts of which are held associated with one another by resilient means, upon a suitable pintle member, so that opening of the clamp is resisted, and with alining means formed on the respective clamping members to hold the same in proper relation during all positions of adjustment.

It is furthermore an important object of this invention to construct a device consisting of similarly formed clamping members recessed at one end to receive a pintle member therebetween, and with a resilient curved element engaging said clamping members to force the same toward one another normally in closed position and maintained upon said pintle member for pivotal movement thereabout.

It is furthermore an object of this invention to construct a clamping device having curved rib portions normally impelled toward one another in closed relation to clamp an article upon a form and each member pro-

vided with heat insulating grips by which the device may be actuated.

It is finally an object of this invention to construct a device simple in construction and operation, and operating efficiently to 60 perform the purpose.

The invention (in a preferred form) is illustrated in the drawings and hereinafter more fully described.

In the drawings:

Figure 1 is a view illustrating an ironing or drying machine shown with a sock drawn thereover and with a clamp embodying the principles of my invention in position to hold the sock upon the form.

Fig. 2 is a front face view of the clamp.

Fig. 3 is a detail section taken on line 3—3 of Fig. 2.

Fig. 4 is an end view of the device.

Fig. 5 is an interior view of one of the 75 clamping members, illustrating the spring in section at the top thereof.

Fig. 6 is a detail section taken on line 6—6 of Fig. 2.

As shown in the drawings:

As illustrated in Fig. 1, the drying or ironing machine consists of a base or pedestal 1, provided with a table top 2, upon which is secured by bolts or other suitable means a hollow form 3. Communicating into said 85 hollow form 3, beneath the table top 2, are inlet and outlet pipes 4 and 5, respectively, by which steam is introduced into the form for the purpose of heating the same, and thereby drying and ironing an article 90 stretched over the exterior thereof. The sock drawn over the form for such a purpose is indicated by the reference numeral 6, and a clamp for holding the same attached thereon is denoted as a whole by the reference 95 numeral 7.

The clamping members of the clamp 7, each consists of a straight flat portion 8, which, when the device is assembled, lie flat against one another as shown in Fig. 2, and 100 are each provided with registering recesses to receive a pintle 9, inserted therein between said clamping members. A resilient curved steel spring 10, engages at its ends in recesses cut in the outer surface of said portions 8, of the clamping members, to hold the same thrust toward one another upon the pintle 9, and to resist opening movement thereof.

Integral with the portions 8, of said re- 110

2

spective clamping members are curved portions 11, and threaded into the same on the outer convex surface thereof, are screws 12, by which wooden knobs 13, are held secured thereto for the purpose of opening the same from one another against the stress of the spring 10. As clearly shown in Figs. 3 and 5, the inner peripheral surface of the curved portions 11, of the respective clamping members are grooved to afford ribs 14, thus affording a plurality of lines of contact for the clamping members when the device is used to hold a sock or stocking in the manner shown in Fig. 1.

15 One of the clamping members is longitudinally slotted at its lower end to afford yoke or fork members 15, as shown in Fig. 4, and the other clamping member, as clearly shown in Figs. 4 and 5, terminates in a single tongue 16, adapted to engage between the yoke members 15, when the clamp is in closed position, as shown in Fig. 2. At the upper ends of the device the respective straight portions 8, of the clamping members each have an oblong slot therethrough, as clearly shown in Figs. 4 and 5, and denoted by the reference numeral 17.

20 Integral with each of the clamping members and disposed at the lower end of the slot 17, of each thereof, and conforming to the curvature of the portion 11, are tongue members 18 and 19, respectively, the one on one side and the other on the other side of the device, so that when the same is in the 25 closed position shown in Fig. 2, said tongue members 18 and 19, respectively, lie against one another and project through said oblong slots. Said respective tongue members 18 and 19, thus serve as an alining means 30 acting with the tongue member 16, and fork members 15, at the lower end of the clamping members to positively maintain the clamping members in proper relation with one another at all times. The upper end of 35 the straight portions 8, of each of the clamping members, as clearly shown in Fig. 2, are tapered off to thus permit the same to open, pivoting about the pintle 9, an extent equal to the angle between said tapered ends, the 40 same being limited in their opening movement by the abutting of said tapered ends one against the other when the device is 45 opened.

50 The operation is as follows:

55 The extent of opening of the clamping members is shown in dotted lines in Fig. 2, from which it will be apparent that the lower ends of the tongue member 16, and yoke members 15, of the respective clamping members do not separate sufficiently to 60 permit insertion or withdrawal of an article therebetween. Consequently there is no possibility of the clamping device being accidentally detached entirely from the form 3, 65 with which it is used, but however, if it is

desired to remove the device therefrom the clamp is loosened by gripping the knobs 13, and springing the clamping members apart as far as possible and then slipping the device off over the end of the form. When used, 70 the sock 6, is drawn over the form 3, and the clamping member is then clamped around the end of the sock.

75 Attention is called to the fact that the parts are held rigidly and securely in operative relation with one another without the use of rivets, bolts or other retaining means beyond the screws 12, which hold the knobs attached to the clamping members, but this is a feature of construction which is immaterial, as the knobs may be attached in any other suitable manner or cast integral with said members if so desired. However, due to the attachment by means of screws, 80 wooden knobs may be used which act as insulating means, preventing the excessive heat from the form being communicated to the handles of the device with the possibility of burning the hands of an operator. The clamping members are maintained in proper 85 relation with one another at all times, due to the interengagement of the respective tongues 18 and 19, through the slots 17, as well as the engagement of the tongue 16, and fork members 15. The upper ends of 90 the clamping members are held tightly upon the pintle 9, by means of the strong spring member 10, which, as pointed out, also resists opening movement of the members.

95 I am aware that various details of construction may be varied through a wide range without departing from the principles of this invention, and I therefore do not purpose limiting the patent granted otherwise than necessitated by the prior art. 100

I claim as my invention:

1. A clamp of the class described comprising clamping members each having central portions curving away from one another, one of said members having a relatively 110 straight tongue formed on the lower end thereof, the other of said members having a relatively straight fork formed on the lower end thereof with which said tongue engages, straight slotted portions formed on 115 the upper ends of each of said clamping members adapted to lie flat against one another and each having a surface recess therein, a pintle engaged in said recesses, resilient means engaging said upper straight portions to maintain said clamping members normally closed against one another, and guiding means on each of said portions engaging in the slot of the other portion. 120

2. In a device of the class described, 125 clamping members each having a straight portion with a recess at one end thereof, a pintle inserted between said members engaging in the recesses thereof, resilient means engaging in notches on the exterior 130

of said members holding the same closely upon said pintle and resisting opening movement thereof, curved portions integral with said straight portions having tongue 5 and fork members formed at the ends thereof to maintain the clamping members in alinement during all adjustments thereof, and means rigidly secured on said clamping members for holding the same apart against 10 the action of said resilient means.

3. A device of the class described comprising clamping members, each having outwardly curved central portions arching away from one another respectively, one of said 15 members having a tongue formed on the lower end thereof, the other member having a fork formed on the lower end thereof with which said tongue slidably engages, straight slotted portions formed on the upper ends of 20 each of said clamping members, a pivotal connection provided at the upper ends of said straight portions of said clamping members, and integral projecting means on each of 25 said clamping members engaging in the respective slotted portions of each of said clamping members to limit the opening movement of said clamping members.

4. In a device of the class described curved clamping members having recesses in the inner surfaces near the upper ends thereof, a 30 pintle engaged in said recesses, means on said clamping members for actuating the same, a curved spring member engaging in recesses cut in the outer surface of each of 35 said clamping members to force the same inwardly toward one another and maintain the same engaged upon said pintle, interfitting tongue and fork members on said respective clamping members to maintain the 40 same in alinement with one another, and

means formed near the upper ends of said clamping members below said pintle to limit the opening movement of said clamping members to insure engagement of said tongue and fork members with one another 45 in all positions of adjustment of said clamping members.

5. A clamp of the class described comprising curved clamping members, each having a straight slotted portion at the upper end 50 thereof, integral projecting means formed on the upper portions of each of said clamping members engaging in the respective slotted portions of one another, tongue and fork members formed on the lower ends of said 55 clamping members interfitting one another to retain the clamping members in alinement in all positions of adjustment, and insulating means on said clamping members to permit opening of the same. 60

6. In a device of the class described clamping members having curved central portions arching away from one another, interfitting tongue and groove members at the lower ends of said clamping members, flat slotted 65 portions at the upper end of each of said clamping members, integral means on each clamping member lying adjacent one another and projecting into the slot of the opposite clamping member, and a resilient 70 member engaging around the ends of said clamping members to hold the same pivotally associated with one another.

In testimony whereof I have hereunto 75 subscribed my name in the presence of two subscribing witnesses.

RICHARD ROOST.
